UNITED STATES PATENT OFFICE

DONALD G. SMELLIE, OF CANTON, OHIO, ASSIGNOR TO THE HOOVER COMPANY, OF
NORTH CANTON, OHIO, A CORPORATION OF OHIO

DESIGN FOR A COMBINED CASING FOR A SUCTION CLEANER AND DUST-BAG RECEP-
TACLE OR SIMILAR ARTICLE

Application filed May 5, 1930. Serial No. 35,495. Term of patent 14 years.

To all whom it may concern:

Be it known that I, DONALD G. SMELLIE, a citizen of the United States, residing at Canton, in the county of Stark and State of Ohio, have invented a new, original, and ornamental Design for a Combined Casing for a Suction Cleaner and Dust-Bag Receptacle or Similar Article, of which the following is a specification, reference being had to the accompanying drawing, forming part thereof,

In the drawing:

Fig. 1 is a side elevation of a casing for a suction cleaner or similar article, showing my new design; and

Fig. 2 is a front elevation of the same.

I claim:

The ornamental design for a combined casing for a suction cleaner and dust bag receptacle or similar article, as shown.

DONALD G. SMELLIE.
